(57) **CLAIM**

The ornamental design for a bottle, as shown and described.

DESCRIPTION

FIG. 1 is a top perspective view of a bottle showing the new design;

FIG. 2 is a front, elevation view thereof;

FIG. 3 is a top plan view thereof; and,

FIG. 4 is a bottom plan view thereof.

The broken lines in the drawings illustrate the portions of the bottle that form no part of the claimed design. The broken lines at the bottom of FIG. 1 and FIG. 2 and the outermost broken line in FIG. 4 define the bounds of the claimed design and form no part thereof.
